A. DIX.

FLUID PRESSURE GENERATOR FOR TURBINES.
APPLICATION FILED OCT. 22, 1917.

1,278,314.

Patented Sept. 10, 1918.

WITNESS:

INVENTOR.

Arthur Dix;

BY *P. J. Barry*

ATTORNEY.

UNITED STATES PATENT OFFICE.

ARTHUR DIX, OF SANTA MARIA, CALIFORNIA.

FLUID-PRESSURE GENERATOR FOR TURBINES.

1,278,314.

Specification of Letters Patent. Patented Sept. 10, 1918.

Application filed October 22, 1917. Serial No. 197,786.

To all whom it may concern:

Be it known that I, ARTHUR DIX, a citizen of the United States, residing at Santa Maria, in the county of Santa Barbara and State of California, have invented a new and useful Fluid-Pressure Generator for Turbines, of which the following is a specification.

This invention relates to a fluid pressure generator and particularly pertains to an apparatus for producing pressure for operating turbines and the like.

It is the object of this invention to provide a fluid pressure generator by means of which steam under pressure may be rapidly formed without the use of boilers and delivered continuously as formed to a turbine or other propulsion mechanism whereby the pressure may be utilized to perform work.

Another object is to provide a simple flash means for generating steam embodying a construction whereby a thin cone-shaped film of water will be projected with a correspondingly shaped intensely hot flame into a pressure chamber in such manner that the flame will instantly convert a major portion of the water into steam.

Another object is to provide means for maintaining the combustion of a fuel oil by an admixture of air therewith within a steam generating chamber.

A further object is to provide a fluid pressure producing apparatus which is simple in construction and operation and which will effect the continuous generation of high fluid pressure with an economical consumption of fuel.

Other objects will appear hereinafter.

The invention is illustrated in the accompanying drawings, in which:

Figure 1 is a view in vertical section and elevation of the fluid pressure forming apparatus.

Fig. 2 is an enlarged section as seen on the line 2-2 of Fig. 1, showing the arrangement of the oil, air and water conduits.

Fig. 3 is a detail section as seen on the line 3-3 of Fig. 1, showing the construction of the burner nozzle.

More specifically 5 indicates a pressure chamber which is here shown as formed of front and rear frusto-conical casings 6 and 7 connected together at their base to provide the chamber with an enlarged central portion converging toward its ends. The outer

end of the chamber 5 has a discharge opening which connects with a nozzle or ejector pipe 8 leading to the turbine or other device to which pressure generated in the chamber is to be delivered. The rear end of the chamber has an inlet opening connecting with a water feed cylinder 9 having a divergent or tapered throat 10 at its intersection with the chamber; the inner wall of the throat being formed in continuation of the inclined inner wall of the casing 7. A water supply pipe 11 connects with the rear portion of the chamber and leads from any suitable source of supply, preferably from a water jacket employed for cooling purposes. Extending axially of the cylinder 9 is an air supply tube 12 having a divergent or cone shaped end 13 the outer face of which conforms to the inner face of the throat 10 and is spaced therefrom. The end 13 forms a spreader for directing water from the cylinder into the chamber in a cone-shaped film and directing it along the inner face of the chamber walls tending to cool the latter. The air tube is preferably mounted for longitudinal adjustment so that the area of the space between the spreader and throat may be regulated to vary the thickness of the stream projected into the chamber, and this is effected by threading the tube where it passes through the end wall of the cylinder as indicated at 14 so that by turning the tube it may be advanced or retracted. The outer end of the tube projects a suitable distance from the cylinder and connects through a union 15 with a hollow cap 16 connecting with an air supply pipe 17 leading from a compressor by which air under pressure may be delivered to the tube.

Extending through the end of the cap and threaded therein for longitudinal adjustment is an oil feed nozzle 18 connected by a union 19 to an oil supply pipe 20. The nozzle 18 is formed with thin walls to readily absorb heat and extends throughout the length of the air tube, the end of the nozzle terminating at the spreader.

A conical tip 21 is disposed over the discharge end of the nozzle for spreading and atomizing the oil ejected therefrom, and is mounted on a tubular stem 22 extending longitudinally through the nozzle and threaded through the oil supply pipe for longitudinal adjustment. A hand wheel 23 on the outer end of the stem is provided for

turning the stem to advance or retract the cone 21.

An electric conductor 24 passes through the stem and connects with a spark terminal 5 25 on the cone insulated therefrom and spaced from spark points 26 grounded on the cone, thus providing an electric ignition device.

Suitable valves 26, 27 and 28 may be provided to regulate the flow of liquids through the pipes 11, 17 and 20, and automatic governors, not shown, may be employed if desired.

In the operation of the invention water is delivered under pressure from the cylinder 9 through the throat 10 into the chamber 5 in a thin cone-shaped film; the tube 12 being adjusted to dispose the spreader 13 in such relation to the divergent walls of the throat 10 as to form the water film of a desired thickness. Air is delivered under pressure through the tube 12 into the apex of the water cone, and fluid fuel is discharged from the nozzle 18 into the body 25 of air at a point within the spreader 13 which fuel is spread by the action of the cone 21 into a cone-shaped spray which is projected into the chamber coincident and substantially concentric with the water film. The fluid fuel being finely atomized is thoroughly intermingled with the air at the mouth of the air supply tube forming a combustible mixture which is ignited by directing an electric current through the spark terminals 25 and 26. The fluid fuel supply being continuous, a cone-shaped flame will be projected interiorly of the cone-shaped water film thus subjecting the water to the direct action of the flames and converting the water into steam. The steam accumulates under pressure in the generating chamber and is discharged through the nozzle 8 to a turbine or other propulsion mechanism. The air discharged through the air supply tube is heated which supplies heat whereby the thin walls of the nozzle 18 are warmed to heat the oil therein to render it more volatile and facilitate its vaporization.

By means of the several adjustments the relative volumes of water, air and fluid fuel may be regulated to obtain a substantially uniform generation of steam.

While I have shown and described a specific embodiment of my invention, it is manifest that various changes may be made in the details of construction without departing from the spirit of the invention as set forth in the appended claims.

Furthermore, while the action and operation of the apparatus has been set forth as applied to steam, it is obvious that the character of gaseous mixture formed in the combustion chamber may be varied according to the relative adjustment of the water, air and fuel oil regulating valves and adjust-

ments. For example, the oil may be delivered in such proportions to the air as to form a large volume of gas, only a minor proportion of which will be burned and which gas with the products of combustion 70 will pass under pressure from the nozzle, and directed to a gas turbine. The water will then act largely as a cooling medium to prevent excessive heating of the parts, and at the same time will afford a supply of steam. 75

I claim:

1. In a fluid pressure generator, a generating chamber, means for delivering water thereto in a cone-shaped film, means for delivering air into the chamber through the 80 apex of the water film, and means for discharging fluid fuel in a cone-shaped spray through the apex of the water film.

2. In a fluid fuel pressure generator, a generating chamber having an inlet and an 85 outlet opening, means for delivering water, air and fluid fuel coincidently into said chamber through the inlet opening, and means for spreading the water, air and fluid fuel in substantially concentric cone- 90 shaped arrangement.

3. In a fluid fuel pressure generator, a generating chamber having an inlet and an outlet opening, means for delivering water, air and fluid fuel coincidently into said 95 chamber through the inlet opening, means for spreading the water, air and fluid fuel in substantially concentric cone-shaped arrangement, and means for regulating the volume of the water and fluid fuel at the 100 spreading point.

4. In a fluid pressure generator, a generating chamber having an outlet and an inlet opening, a water feed cylinder connecting with the inlet opening, air supply 105 tube leading to the chamber through said water cylinder and a fluid fuel nozzle projecting through said air tube.

5. In a fluid pressure generator, a generating chamber having an outlet and an 110 inlet opening, a water feed cylinder connecting with the inlet opening, an air supply tube leading to the chamber through said water cylinder, a fluid fuel nozzle projecting through said air tube, and means for 115 adjusting said fuel nozzle longitudinally in said tube.

6. In a fluid pressure generator, a generating chamber having an outlet and an inlet opening, a water feed cylinder connecting 120 with the inlet opening, an air supply tube leading to the chamber through said water cylinder, means for adjusting said tube longitudinally in said cylinder, and a fluid fuel nozzle projecting through said air tube. 125

7. In a fluid pressure generator, a generating chamber having an outlet and an inlet opening, a water feed cylinder connecting with the inlet opening, an air supply tube leading to the chamber through said 13

- water cylinder, means on said air supply tube for spreading water discharged from the cylinder into the chamber, and a fluid fuel nozzle projecting through said air tube.
5. 8. In a fluid pressure generator, a generating chamber having an outlet and an inlet opening, a water feed cylinder connecting with the inlet opening, an air supply tube leading to the chamber through said water cylinder, means on said air supply tube for spreading water discharged from the cylinder into the chamber in a cone-shaped film, means for adjusting said tube longitudinally to vary the thickness of the water film, and
10. 15. a fluid fuel nozzle projecting through said air tube.
9. In a fluid pressure generator, a generating chamber having an enlarged central portion tapering to inlet and discharge
20. 20. openings at its extremities, a water feed cylinder connecting with the inlet opening having an outwardly flared throat conforming to the tapered inlet wall of the chamber, an air supply tube opening to the chamber through the water cylinder, a cone-shaped spreader on said tube arranged in the tapered throat, a fluid fuel supply nozzle arranged to discharge into the chamber through said spreader, means on said nozzle for spreading the fluid fuel ejected therefrom, means for adjusting the water spreader and means for adjusting the fluid fuel spreader.
- 40
11. In a fluid pressure generator, a generating chamber having an outlet and an inlet opening, a water feed cylinder connecting with the inlet opening, an air supply tube leading to the chamber through said water cylinder, a fluid fuel nozzle projecting through said air tube, and adjustable means 45 for spraying fluid fuel discharged from said nozzle.
- 50
12. In a fluid pressure generator, a generating chamber having an outlet and an inlet opening, a water feed cylinder connecting with the inlet opening, an air supply tube leading to the chamber through said water cylinder, a fluid fuel nozzle projecting through said air tube, adjustable means 55 for spraying fluid fuel discharged from said nozzle, and means for electrically igniting the fluid fuel.
- 60
- 65
10. In a fluid pressure generator, a generating chamber having an enlarged central portion tapering to inlet and discharge

ARTHUR DIX.
